UNITED STATES PATENT OFFICE

THOMAS J. SCOTT, OF FOLEY, ALABAMA, ASSIGNOR TO SWANN RESEARCH, INC., A CORPORATION OF ALABAMA

PROCESS AND APPARATUS FOR THE PRODUCTION OF DIPHENYL

Application filed June 2, 1928. Serial No. 282,403.

This invention relates to a method and apparatus for making diphenyl by raising the temperature of benzene, or the commercially known product benzol, to the temperature at which diphenyl is formed.

One of the objects of this invention is to produce diphenyl on a commercial scale, by a method in which it is easier to control the temperature, rate of flow of gas, and obtain quick cooling of the vapor, than by any method heretofore proposed; and further, to produce diphenyl more economically than is possible by any existing methods.

A further object of the invention is to provide an apparatus in which this method of production may be carried out.

A still further object is to provide a method of supplying the heat necessary for the reaction whereby the tendency for the formation of carbon is lessened, and to provide a means whereby such carbon as may be formed may be removed from the reaction system without interruption of the continuity of the process.

So far as I am aware, the production of diphenyl on a commercial scale is carried out, only by passing benzene vapor over a surface which is heated by electrical means. I have discovered a means of heating benzene vapor by means of fuel heat, such as gas, oil, or solid fuel, for instance, and in an apparatus which is easier to control, whereby the factors relating to the reaction are under the necessary control, thereby producing diphenyl by an improved method, and at a lower cost.

The factors which I have found to be of greatest importance, influencing the successful production of diphenyl, are:

1. Means of controlling the temperature in the reacting zone in such a manner that the reacting temperature is maintained, but excessive temperature is avoided.

2. Supplying all the heat possible for pre-heating the gas, at a temperature at which little or no diphenyl will be formed.

3. After the preheating, to subject the benzene vapor for a very short time at a temperature for the optimum formation of di-

phenyl, with the minimum side reactions occurring.

4. Providing a means of definite control of the reacting temperature, whereby sufficient heating (i. e. temperature rise) will be obtained, but overheating will be prevented.

5. Quickly cooling the vapor after its contact at the reacting temperature, to prevent reversal of the diphenyl equilibrium and the reformation of benzene.

I am able to accomplish all the foregoing in the method I propose and the apparatus which I employ.

In order that my method may be more clearly understood and be practiced by those who are skilled in the art, I will now describe my method, as follows:

Benzol which may be in either a liquid or a vapor form is pumped through a coil of pipe which is immersed in a molten lead bath maintained at a temperature at which substantially no diphenyl is formed. This coil acts as a preheater, and serves to lessen the time of contact of the benzol with the higher temperature heating zone and thus avoids objectionable side reactions. When the benzol remains too long in a zone heated to that at which substantial quantities of diphenyl is formed excessive tar is formed along with the diphenyl. If the benzol is first introduced in a liquid form it is vaporized soon after it enters the pipe, and passes thereafter through the coil, during which passage it absorbs heat from the walls of the pipe and reaches the temperature of the bath by the time it passes therefrom. The coil which is at the bottom of the bath is perforated, and the vapor streams out and in rising through the molten lead, in physical contact therewith, agitates the bath in such a manner as to maintain a practically uniform temperature through the bath. By employing a large mass of lead, I am enabled to prevent overheating of the vapor due to the heat capacity of the bath, and by means of a thermocouple immersed therein, to observe temperature changes which may occur, and change the heating so as to supply additional heat or lessen the rate of heating, as may be desired. I prefer to operate the preheater bath at a tempera-

ture from 600° to 650° C., and have found from experience that this is the optimum temperature range for most continuous operation. If the temperature exceeds 650°, tar or other liquids boiling above diphenyl are formed in the preheater.

After the preheated vapor emerges from the preheater bath, it is immediately passed into a converter bath which is of similar design and arrangement as the preheater. The vapor passes to the bottom of the bath and streams out through holes in a distributor, and then bubbles up through the lead in a manner similar to the preheater. The converter bath is kept at a temperature range of from 750° to 800° C. When the vapor passes from the converter bath it is passed, at a high velocity, directly into a water-cooled condenser, so constructed that the vapor is quickly cooled and the unconverted benzene and the diphenyl are condensed and collected, while the hydrogen which is liberated when diphenyl is formed, is vented through a gasometer.

In vaporizing the benzol and heating the vapors thereof there is an increase in volume amounting to substantially 800 times the original volume of the liquid benzol. The heated vapors are passed through conduits of such cross sectional area that the velocity of the vapors is greatly increased over the velocity of the liquid benzol fed to the heaters.

In operating my method according to the foregoing description, I am able to obtain from 10% to 12% diphenyl formed per pass through the converter bath. If higher temperatures of the converter bath are employed, a higher yield of diphenyl will be obtained; however, the side reactions will form tarry bodies, and carbon will be formed, thereby uselessly consuming benzene.

Apparatus in which my improved method is carried out is illustrated in the accompanying drawings, forming a part of this application, wherein

Fig. 1 is a plan view of the apparatus;

Fig. 2 is a sectional view taken along the line II—II of Fig. 1; and

Fig. 3 is an enlarged plan view of the coil employed in the lower portion of the molten metal baths.

Referring to the drawings, I show a furnace 10 having separate heating chambers 11 and 12, divided by a wall 14 and each supplied with a fuel oil burner 13. In the chamber 11 is a vessel 16 and in the chamber 12 is a vessel 17, each of the vessels being filled to the level shown in the drawing with a substance 18, such as lead, which is molten at the temperatures employed. The chamber 11 is provided with a baffle wall 19 and the chamber 12 is provided with a baffle wall 21 which walls direct the heated products of combustion around the vessels 16 and 17 so that the heat is evenly distributed thereto. After passing around

the vessels the combustion gases unite and pass outwardly through a common flue 22. Each of the vessels is supplied with a gas-tight cover 23. Extending downwardly into the vessel 16 is a coil of pipe 26 and extending downwardly into the vessel 17 is a pipe 27. Each of the pipes 26 and 27 terminates in a bottom coil 28, such as is shown in detail in Fig. 3, and having a plurality of openings 29 therein, to permit vapor to pass upwardly through the molten metal in the vessel.

Across the upper end of each of the vessels 16 and 17 is a baffle 31 to prevent the carrying over of molten metal with the gases passing through the bath. Extending downwardly through the cover 23 of the vessel 16 is a pipe 32 for conveying gases away from the vessel 16 and which connects, through a conduit 33, with the pipe 27 extending downwardly into the vessel 17 and which connects with a header 35 having connected thereto a plurality of conduits 37 each provided with a water jacket 38 having inlet and outlet connections 41 and 39 for quickly cooling the heated vapor after it passes from the vessel 17. The other ends of the conduits 37 are connected to a header 40. After passing through the water cooled condensing conduits 37, the condensate flows through a U-tube 46, connected to the header 40, and through a conduit 47 to a receiving tank 48. Connected to the header 40 is a vent 45 for hydrogen and other uncondensed gases. The U-tube 46 is provided with a sight glass 49 for observing the condensate. The storage tank 48 is provided with a breather vent opening 51 to permit ready filling and emptying thereof.

In order that the temperatures within the vessels 16 and 17 may be observed and the supply of fuel regulated to give the desired heat, I provide thermo-couples 53 and 54 in the vessel 16 and which are connected to the outlet for the vapor and into the molten metal respectively. Similarly, the vessel 17 is provided with thermo-couples 56 and 57 to indicate the temperatures of the outlet vapor and the molten metal in the vessel. I also provide gauges 58 to indicate the pressures of the benzol being pumped into the vessels and the outlet pressures of the vapor as it leaves the vessels.

Benzol is supplied to the apparatus from a suitable source of supply through a conduit 61 connected to a pump 62 and is discharged through a conduit 63 connected to the coil 26. After being heated and condensed and collected in the storage tank 48, the condensate is drained off through a conduit 64 for fractional distillation in a well known manner.

In order that there shall be no danger of explosions at starting, I provide a conduit 66, connected to the conduit 63 for forcing an inert gas, such as carbon dioxide, through

the pipe and vessels before the benzol pump 62 is started. The conduit 66 is provided with suitable valves 67 and 68 for controlling the supply of inert gas while the conduit 63 is provided with a valve 69 which is to be closed when the inert gas is being forced through the system.

From the foregoing description the operation of my improved apparatus will be apparent. Benzol is forced by the pump 62 through the conduit 63 into the coil 26 from which it bubbles upwardly through the molten metal in the vessel 16, which molten metal is maintained at a temperature range of from 10 600° to 650° C., for preheating the benzol vapor. The preheated vapor passes quickly through the conduits 32 and 33 into the pipe 27 leading to the coil 28 in the bottom of the vessel 17, where the temperature range is 15 from 750° to 800° C., the temperature at which diphenyl is formed. The pipe 27 is made straight, except for the coil 28, in order that the vapor shall be in contact with the higher temperature bath only a sufficient time 20 to raise it to the required temperature. After bubbling upwardly through the molten metal in the vessel 17 the vapor is immediately conveyed to the water cooled conduits 37 where it is condensed and flows to the storage tank 48.

While there is an enormous increase in the volume of the benzol as its temperature is raised, the conduits through which the vapor is conveyed are not correspondingly increased in cross sectional area, so that the 25 velocity of the vapor is progressively increased as it passes through the apparatus. This is extremely important in that it prevents reversal of the process and also prevents objectionable side reactions while the vapor is in the heated zone.

From the foregoing, it will be apparent that I have devised an improved method and apparatus for the production of diphenyl which is operable upon a commercial scale 40 and wherein the temperature, rate of flow of vapor, and cooling of the vapor are under such control that a higher yield than has heretofore been possible is readily obtained.

While I have shown my invention in but one form, it will be obvious to those skilled in the art that it is not so limited but is susceptible of various changes and modifications without departing from the spirit 45 thereof and I desire therefore that only such limitations shall be placed thereupon as are imposed by the prior art, or as are specifically set forth in the appended claims.

60 What I claim is:

1. The process of producing diphenyl which consists in passing benzol vapors through a bath of a molten substance inert with respect to the vapors and heated to a 65 temperature at which substantial quantities

of diphenyl are formed, and condensing the vapors.

2. The process of producing diphenyl which comprises passing benzol vapors through a bath of a molten substance inert 70 with respect to the vapors and heated to the maximum temperature at which substantially no diphenyl is formed, and immediately thereafter passing the vapors thus heated through a similar bath heated to the temperature 75 at which substantial quantities of diphenyl are formed.

3. The process of producing diphenyl which comprises passing benzol vapors through a bath of a molten substance inert 80 with respect to the vapors and heated to the maximum temperature at which substantially no diphenyl is formed, immediately thereafter passing the vapors thus heated through a similar bath heated to the temperature at 85 which substantial quantities of diphenyl are formed, and immediately thereafter cooling the vapors thus heated to condense them.

4. The process of producing diphenyl which comprises passing benzol vapors 90 through a bath of a molten substance inert with respect to the vapors and heated to the maximum temperature at which substantially no diphenyl is formed, immediately thereafter passing the vapors thus heated through 95 a similar bath heated to the temperature at which substantial quantities of diphenyl are formed, immediately thereafter cooling the vapors thus heated to condense them, and distilling the condensate to separate the diphenyl.

5. The process for producing diphenyl which comprises passing benzol vapors progressively through a pair of molten metal baths heated respectively to from 600° to 650° 100 C., and 750° to 800° C.

6. The process for producing diphenyl which comprises passing benzol vapors progressively through a pair of molten metal baths heated respectively to from 600° to 110 650° C. and 750° to 800° C., and quickly cooling the vapors thus heated while at a high velocity.

7. The process of obtaining diphenyl from benzol which comprises passing benzol vapors upwardly through a bath of molten metal heated to a temperature at which diphenyl is formed, and quickly cooling the heated vapors to prevent reversal.

8. The process of obtaining diphenyl from benzol which comprises vaporizing liquid benzol by subjecting it to the heat of a molten metal bath heated to a temperature at which substantially no diphenyl is formed, forcing 125 said vapors upwardly through the molten metal in contact therewith to preheat said vapors, forcing the vapors thus preheated through a second molten metal bath heated to a temperature at which diphenyl is formed, 130

and quickly cooling the vapors to condense the diphenyl.

9. The process of obtaining diphenyl from benzol which comprises passing benzol vapors in heat transfer relation with a fluid medium inert with respect to the benzol vapors and heated to a temperature at which substantially no diphenyl is formed, and immediately thereafter passing the vapors thus preheated in heat transfer relation with a second similar fluid medium heated to a temperature at which diphenyl is formed.

10. The process of obtaining diphenyl from benzol which comprises passing benzol vapors in heat transfer relation with a fluid medium inert with respect to the benzol vapors and heated to a temperature at which substantially no diphenyl is formed and immediately thereafter passing the vapors thus preheated in heat transfer relation with a second similar fluid medium heated to a temperature at which diphenyl is formed, and quickly cooling the vapors thus heated to condense the diphenyl and unreacted benzol and to prevent reversal of the process.

11. Process of making diphenyl which comprises contacting benzol vapor with an inert liquid mass maintained at a temperature sufficient to decompose the benzol.

12. Process of making diphenyl which comprises passing benzol vapor through a body of inert liquid maintained at a temperature sufficient to decompose the benzol.

13. Process of making diphenyl which comprises passing benzol vapor through a body of molten lead maintained at a temperature sufficient to decompose the benzol.

14. Process of making diphenyl which comprises heating benzol vapor to a temperature below but approaching the decomposition temperature of the benzol and delivering the heated benzol vapor into contact with a body of inert liquid maintained at a temperature sufficient to decompose the benzol.

15. In testimony whereof I affix my signature,

THOMAS J. SCOTT.
